F. ORDAKOWSKI,
DEVICE FOR RETAINING OVERSHOES ON SHOES,
APPLICATION FILED MAY 18, 1922.

Patented Oct. 24, 1922.

Felix Ordakowski
J. A. Mathews
Attorney

UNITED STATES PATENT OFFICE.

FELIX ORDAKOWSKI, OF CLARKSBURG, WEST VIRGINIA.

DEVICE FOR RETAINING OVERSHOES ON SHOES.

Application filed May 18, 1922. Serial No. 561,972.

To all whom it may concern:

Be it known that I, FELIX ORDAKOWSKI, a citizen of the United States, residing at Clarksburg, in the county of Harrison and State of West Virginia, have invented certain new and useful Improvements in a Device for Retaining Overshoes on Shoes, of which the following is a specification.

My invention relates to a device for use in connection with rubbers or overshoes, for retaining them upon the shoes, and preventing improper displacement thereof.

An important object of the invention is to provide a device of the above mentioned character, which is of simplified construction, and is self-adjusting to permit of the bending of the ankle.

A further object of the invention is to provide a device of the above mentioned character which is adjustable within limits, for connection with shoes of different heights.

Other objects and advantages of the invention will be apparent throughout the course of the following description.

In the accompanying drawings forming a part of this specification and in which like numerals are employed to designate like parts throughout the same,

Figure 1 is a perspective view of a device embodying my invention, showing the same applied to an overshoe and shoe,

Figure 2 is a perspective view of the device removed,

Figure 3 is a longitudinal section through the clamp,

Figure 4 is a perspective view of a modification of the device, and,

Fig. 5 is a perspective view of the device shown in Fig. 2, showing a slightly different use.

In the drawings, wherein for the purpose of illustration is shown a preferred embodiment of my invention, the numeral 5 designates an overshoe, and 6 the upper of the shoe.

My retaining device embodies a strip 7, formed of sheet metal or the like, having laterally extending stop lugs 8, formed thereon. The strip 7 is provided at its top with curved ears 9, slidably receiving a coacting strip 10, also preferably formed of sheet metal. The strip 10 is provided at its lower end with curved ears 11, slidably engaging the strip 7 beneath the stop lugs 8, and adapted to contact with the stop lugs.

It is thus seen that the strip 10 is free to

move longitudinally with relation to the strip 7, the distance between the ears 10 and stop lugs 8. At its upper end, the strip 10 is bent inwardly and downwardly, forming a hook 12, engaging over the upper edge of the upper 6.

The clamp is carried by the lower end of the strip 7 and this clamp preferably embodies spaced sides 13, carried by a bottom 14, preferably serrated upon its inner side, as shown at 15. The sides 13 are extended in the form of arms 16, within which is pivoted, at 17, a lever 18. This lever carries a compression element or roller 19, eccentric with the pivot 17, and adapted to press the material of the rubber into engagement with the serrations 15.

In the use of this form of the device, the hook 12 is placed over the top of the upper 6, as shown in Figure 1, while the clamp engages over the upper portion of the back of the overshoe 5. The strip 10 may move longitudinally sufficiently with relation to the strip 7, to permit of the bending action of 80 the ankle. The device will prevent any undue movement of the overshoe 5 downwardly with respect to the shoe, by stop lugs 8 contacting with the ears 11.

In Figure 5, the hook 12 is shown engaging over a strap 12', which encircles the ankle of the wearer. This strap is employed when the device is used with slippers or low shoes.

In Figure 4, I have shown a slight modification of the device, and this modification is designed for use in connection with high shoes, frequently worn by women. In this form of the device, the strip 10 is dispensed with and the strip 7 slidably engages an intermediate strip 20. The strip 20 is provided at its lower end with curved ears 21, arranged beneath the stop lugs 8, and adapted to contact therewith. The intermediate strip 20 is in engagement with an upper adjusting strip 22, provided at its lower ends with curved ears 23, slidably receiving the strip 20. The strip 20 is provided at its top with a hooked tongue 24, adapted for insertion within selected spaced openings 25 in the strip 22. The adjusting strip 22 has its upper end bent downwardly into a hook 16, to engage over the top of the upper. It is obvious that the length of the device may be permanently adjusted by placing the tongue 24 in a selected opening 25, and when the device is applied to the shoe, the inter-

mediate strip 20 will slide with relation to the strip 7, within the limits of the distance between the stop lugs 8 and the ears 21. The same form of clamp is carried by the 5 strip 7.

It is to be understood that the forms of my invention herewith shown and described are to be taken as preferred examples of the same, and that various changes in the shape, 10 size, and arrangement of parts may be resorted to without departing from the spirit of the invention or the scope of the subjoined claims.

Having thus described my invention, I 15 claim:

1. A retaining device for overshoes, comprising a strip provided with ears and having laterally extending stop lugs, a co-acting strip held within the ears and having 20 ears slidably receiving the first named strip and adapted to engage with the stop lugs, said co-acting strip being permanently free to slide upon the first named strip whereby said strips automatically partake of relative longitudinal movement upon the bending 25 of the ankle in walking, a hook formed upon one end of the co-acting strip, and a clamping device carried by the other strip.

2. A retaining device for overshoes, com-

prising a pair of co-acting strips slidably engaging, and permanently free to move longitudinally with relation to each other means whereby one strip may be automatically moved longitudinally with relation to the other upon the bending of the ankle in 30 walking and positively limiting such longitudinal movement in one direction, a holding element carried by one of the strips to engage over the top of the upper, and a clamp carried by the other strip to engage with the 35 overshoe.

3. A retaining device for overshoes, comprising a pair of co-acting strips slidably engaging each other, said coacting strip being permanently free to slide upon the first 40 named strip means to permit one strip to automatically move longitudinally with relation to the other upon the bending of the ankle in walking and positively limiting such longitudinal movement in one direction, a clamping device carried by one strip to engage with the overshoe, and an adjusting strip longitudinally adjustably mounted upon the other strip and adapted to engage 45 over the top of the upper.

In testimony whereof I affix my signature.

FELIX ORDAKOWSKI.
